[57] CLAIM

The ornamental design for a men's and women's fashion container, as shown and described.

DESCRIPTION

FIG. 1 is a perspective view of a men's & women's fashion container showing my new design;

FIG. 2 is a top view thereof;

FIG. 3 is a bottom view thereof;

FIG. 4 is a front elevational view thereof, the back view being a substantial mirror image thereof;

FIG. 5 is a side elevational view thereof, the opposite side being a substantial mirror image thereof;

FIG. 6 is a top view thereof with the upper zippered portion opened and folded down with typical fashion implements shown in phantom;

FIG. 7 is a front elevational view of the men's & women's fashion container shown in FIG. 6;

FIG. 8 is a back elevational view of the men's & women's fashion container shown in FIG. 6; and,

FIG. 9 is a side elevational view of the men's & women's fashion container shown in FIG. 6, the opposite side being a substantial mirror image thereof.

The broken line showing of fashion implements in FIG. 6 is for illustrative purposes only and forms no part of the claimed design.
